MUSICAL INSTRUMENT PAD

Eugene Sander, Elkhart, Ind., assignor to H. & A. Selmer, Inc., Elkhart, Ind., a corporation of Indiana

Application February 28, 1941, Serial No. 381,063

7 Claims. (Cl. 84—385)

This invention relates to musical instrument pads, and more particularly to valve pads or gaskets for use on musical instruments of the woodwind type, of which the saxophone, clarinet, flute, oboe, and bassoon are examples.

The pads which are now in common use are formed from a layer of felt backed by a layer of paper or cardboard and covered by a layer of kidskin or bladder skin which is folded around the marginal edges of the felt and paper and adhesively secured to the back face of the paper. These pads are expensive to manufacture, require heat to seat them on the instruments, and tend to absorb sound. Attempts have been made to develop pads which will overcome these objections, as by using pads of rubber molded to shape, etc., but these have been objectionable for various reasons.

The primary object of the instant invention is to provide a pad of this character which overcomes the deficiencies of previous pads, and which imparts improved playing properties to an instrument.

A further object is to provide a pad of this character which will provide an improved seal at the valves of an instrument.

A further object is to provide a pad of this character constructed to become somewhat of a reflector for vibrations and thereby give greater volume of sound when an instrument on which it is used is played or blown, but which will not increase the noise of the mechanical operation of the valve closure per se which is commonly referred to as "pad slap."

A further object is to provide a pad of this character which need not be heated to crease it for proper seating in association with a cooperating valve part.

A further object is to provide a pad of this character which is of laminated construction and can be cut to size from a sheet of laminated material.

A further object is to provide a pad of this character which gives quicker tone response to valve operation, which separates the tones during operation of an instrument, and which imparts improved and increased clarity of tone in playing of an instrument.

A further object is to provide a novel, simple, and inexpensive method of making a pad of this character.

A further object is to provide a pad of this character which is simple to manufacture and which is inexpensive.

Other objects will be apparent from the description, drawing, and appended claims.

In the drawing:

Fig. 1 is a side view of a saxophone, with parts of the saxophone illustrated by dotted lines in outline only to simplify the drawing.

Fig. 2 is a transverse sectional view taken on line 2—2 of Fig. 1 and illustrating a valve in open position.

Fig. 3 is a longitudinal sectional view taken on line 3—3 of Fig. 2, and illustrating a valve in closed position.

Fig. 4 is a view similar to Fig. 3 but illustrating a different construction of valve with which my improved pad may be used.

Fig. 5 is a perspective view of a valve pad adapted for use with a valve illustrated in Fig. 4.

Fig. 6 is a perspective view of a valve pad adapted for use with the valve construction illustrated in Figs. 3 and 2.

Fig. 7 is a transverse sectional view of the valve pad illustrated in Fig. 5.

Fig. 8 is a transverse sectional view of the valve pad illustrated in Fig. 6.

Fig. 9 is a fragmentary face view of a sheet of laminated material from which valve pads of various sizes may be cut as illustrated therein.

In the drawing, parts of the saxophone 10 are illustrated diagrammatically only and in dotted

30 lines for the purpose of simplification of the drawing. It will be understood, however, that the saxophone comprises the usual tubular body, including the stack 11, the bell 12, the mouth pipe 13, and the mouth piece 14, together with the 35 usual valves for the various tone holes and octave vents in the tubular body.

The various tone holes of the instrument may be provided with valves in any desired type. In Figs. 2 and 3, I have illustrated the same as of

40 the construction covered by my Patent No. 2,227,230, dated December 31, 1940. In this construction, the tone hole is outlined by an annular metal member 15, projecting perpendicularly

45 outwardly from stack 11. An annular member 16 fits around the ring 15 and is of substantially L shape in cross section, being provided with an outwardly directed flange 17 spaced from ring 15. Annular member 15 and flange 17 of annular member 16 cooperate to form an annular

45 groove adapted to receive an annular gasket or pad 18, whose outer portion projects from said groove. A valve plate 19, which may have an annular projection 20 at its inner face as shown in Fig. 3, is adapted to seat on gasket 18, and is

50 mounted upon an arm 21 pivoted at 22 to a suit-
55

able support 23 carried by the tubular body of the instrument. In Fig. 4, which is a view similar to Fig. 3, I have illustrated the conventional form of tone hole, and valve construction wherein the tone hole is outlined by an annular member 25 projecting from the tubular body of the instrument. The outer edge of member 25 is adapted to be engaged and sealed by a gasket or pad 26 suitably carried by a valve plate 27 which is mounted upon the pivoted arm 21.

Considering now the construction of the pad or gasket of the present invention and referring to Figs. 5 to 9, inclusive, for this purpose, both annular pad 18 for use in the instrument valve illustrated in Figs. 2 and 3, and disc pad 26 for use in the instrument valve illustrated in Fig. 4 are of identical construction except for their respective shapes. Each of these gaskets or pads has a laminated body, as best illustrated in Figs. 7 and 8. Referring first to Fig. 7, the laminated pad body comprises a base layer 30 formed of paper or cardboard. The next layer 31 of the basket is formed from a soft leather or other soft material having at least a small measure of resilience. A layer 32 of gum rubber or other material having a very high degree of resilience is superimposed upon layer 31. The outer or face layer 33 is formed of kidskin, or like material. The various layers are cemented together by the use of a flexible cement, of which one example is a latex cement. The primary characteristics required of this cement are that it be flexible and substantially non-hardening so as to avoid interference with the properties of compressibility and resilience possessed by the various layers of the pad.

It will be understood that the character of the various layers as above described is illustrative only and not limiting. Thus, for example, while a soft sheepskin leather is preferable for layer 31, felt, calfskin or other soft leather, cloth in the order of $\frac{1}{2}$ of an inch thick, as for example the cloth used for men's overcoats, and other materials may also be used for layer 31. The characteristics which the material of which layer 31 is formed should provide a certain small degree of resilience and the property of dampening closure or mechanical noises.

The layer 32 is preferably made of pure gum rubber, soft black rubber, sponge rubber, or any other material which is very soft and has a very high degree of resilience, i. e. a quick return from compressed to normal position. This layer assists in avoiding pad slap by virtue of its softness and compressibility, but does not tend to absorb or dampen the tone or vibrations of the instrument to any appreciable extent, but rather may be said to act somewhat as a reflector of such tones and vibrations.

The layer 33 is preferably formed from kidskin. However, other materials which may be used therefor are bladder skin provided with a thin felt backing, rubber impregnated cloth, such as that material commercially called "Pliofilm," and thin sheets of synthetic material, such as a vinyl. The primary requirements of this layer are that it shall be able to take a crease, that it shall be resilient with a slow comeback from compressed to normal position, that it shall be air-tight, and that it shall be moisture resistant to at least the same extent that kidskin is moisture resistant.

It will be understood that the various laminations of the material above described must each be adhesively secured to adjacent lami-

nations throughout the full extent to the faces thereof. For purposes of simplicity, ease, and cheapness of manufacture, large sheets of the respective layers are coated with thin uniform films of the cement, and are then pressed together to obtain continuous adhesion of the faces thereof to provide a large laminated sheet 34, as illustrated in Fig. 9. The gaskets or pads are then cut from this sheet, and may also be coated at their cut edges with lacquer, or other flexible sealing or coating compound. Hence, by making the laminated sheets 34 of large size, it is possible to obtain a large number of gaskets or pads of different sizes by merely cutting them from the sheet 34. This simple process of forming a laminated sheet and cutting individual elements therefrom has the obvious advantages of simplicity and cheapness, and avoids the steps of separately forming individual elements and then assembling the same as is now practiced in the manufacture of conventional pads.

The primary purpose of the paper or cardboard layer 30 illustrated in Fig. 7 is to provide a back which will readily take cement required to secure the gasket or pad to the part of the instrument which is to carry the same. Also, the paper may serve as a shim to properly position the pad relative to its mounting member. The paper plays no other appreciable function in the pad, and may be eliminated entirely if desired, as illustrated in Fig. 8. The only requirement in the event paper 30 is eliminated is that the material of which layer 31 is formed shall be such as to be readily glued to a mounting member.

Inasmuch as the laminations are formed of soft material, the edges thereof are raw and severed, and the pad edges may be at least partly exposed when the pad is mounted on the instrument; it is possible that said edges when formed of the material specified, may be frayed, split or roughened in handling. Hence, it may be desired to protect the edges of the pad. This can be accomplished by applying a layer 35 of lacquer or other suitable sealing or coating compound thereto, as illustrated in Fig. 8. An annular gasket may have a layer 35 of lacquer applied to both the inner and the outer peripheries of the pad.

A gasket or pad of the character and construction above described has many advantages over pads heretofore developed and used for musical instruments. The principal advantage of this type of pad is that it imparts improved playing properties to a woodwind instrument on which it is used. The playing properties of an instrument depend in large measure on the resulting characteristics of the valve pad. Thus, the air sealing properties of a pad are very important in a musical instrument. This new pad provides a much better air seal at the valve than does any conventional type of gasket, and almost completely eliminates air leakage through the body of the pad itself. In this connection, note that the high degree of resilience and quick return from compression of the gum rubber layer, coupled with the imposition of a thin layer of sheepskin in direct face contact upon the gum rubber, insures this improved air seal. Also, the use of this type of gasket upon an instrument also increases the playing volume of that instrument. The outer or face and intermediate layers of the pad have very little porosity as compared with the conventional type of pad which employs a felt body, and hence the new pad has somewhat the prop-

erties of a sound or vibration reflector. At the same time, the layers 31 and 32 impart to the pad the property of absorbing mechanical noises and "valve slaps" sounds incident to valve operation. In fact, the maintaining of mechanical valve operating noises at a minimum, while increasing the playing volume of the instrument, is one of the outstanding advantages of the above-described pad construction. Additionally, the playing of instruments provided with my new pad also discloses that the pad gives the instrument a quicker response to valve operation. This quick response separates the successive tones of the instrument responsive to successive valve operations much more clearly and distinctly than is true with instruments provided with conventional pads. This tone separation thus clearly improves the clarity or playing of the instrument. Another important advantage of the instant pad is that it need not be heated to crease the same for the purpose of seating it with respect to the valve part bearing thereagainst. The conventional type of gasket pad requires heating in order to seat the pad, and this is particularly objectionable in cases where an instrument must be supplied with new pads for replacement purposes. This new pad also has a superior resistance to water and moisture as compared to conventional pads, which, among other advantages, permits an instrument provided with the pad to maintain its regulation for a long period by eliminating the swelling which often necessitates realignment of the playing mechanism.

I claim:

1. A valve pad for woodwind instruments comprising an outer layer of kidskin, an intermediate layer of soft gum rubber, and an inner layer of soft sheep skin leather, said layers being superimposed and adhesively secured together throughout their full extent by a flexible non-hardening cement.

2. A valve pad for woodwind instruments comprising a paper back, a layer of soft leather superimposed on said back, a layer of soft rubber superimposed on said leather, and a layer of kidskin superimposed on said rubber, said layers being secured together in face contacting engagement by a flexible non-hardening cement.

3. A valve pad for woodwind instruments comprising a paper back, a layer of soft leather superimposed on said back, a layer of soft rubber superimposed on said leather, a layer of kidskin superimposed on said rubber, said layers being secured together by a flexible cement, and the

marginal edge of said pad being bound by a layer of flexible sealing compound.

4. A valve pad for woodwind instruments comprising a laminated body cut to desired size and shape, said body comprising a thin flexible moisture resistant face layer, a soft highly resilient intermediate layer having relatively low sound absorbing properties, and a soft resilient inner layer of a material having relatively high sound absorbing properties, and a thin film of non-hardening cement interposed between adjacent layers to adhere said layers in full face engagement.

5. A valve pad for woodwind instruments comprising a laminated body cut to desired size and shape, said body comprising a base layer of compressible material, a soft intermediate layer of material having greater resilience than the material of said base layer, and an outer layer of material characterized by low porosity, flexibility, moisture resistance, and a thickness less than said intermediate layer, and a thin film of flexible cement interposed between adjacent layers to secure said layers in superimposed relation throughout their full area.

6. A valve pad for woodwind instruments comprising a laminated body cut to desired size and shape, said body comprising an outer lamination of thin flexible moisture resistant sheet material, an intermediate lamination of a solid material characterized by a high degree of compressibility and resilience, and a yielding inner lamination, and a thin film of flexible cement between laminations uniting said laminations in full face engagement, said outer and intermediate laminations having low degrees of porosity and sound absorption and said inner lamination having a comparatively higher degree of porosity and mechanical noise absorption.

7. A laminated valve pad for woodwind instruments comprising an outer lamination of thin flexible material of the class including kidskin, bladder skin, rubber impregnated fabric, and flexible synthetics such as vinyl, an intermediate layer of resilient material of the class including soft gum rubber, soft black rubber, soft synthetic rubber and sponge rubber, and an inner layer of soft material characterized by a porosity and compressibility greater than said outer lamination and of the class including sheepskin leather, salfskin, felt, and thick fabric, said laminations being flexibly adhered in face contacting engagement through their full extent.

EUGENE SANDER.
